UNITED STATES PATENT OFFICE

2,026,630

SHEARING DEVICE

Artie B. Harris, Kansas City, Mo.

Application June 19, 1933, Serial No. 676,507

11 Claims. (Cl. 30—1)

My invention relates to shearing devices and more particularly to those of the rotary type wherein a cutter is rotatably mounted within a guard and has for its principal object to provide 5 a more efficient cutter construction that retains its keen cutting properties over long periods of use.

Other important objects of the invention are to provide for automatic, self-tensioning of a cutter relatively to its guard, to provide flexible coupling of the cutter with its driving shaft, to provide a flexible cutter to freely accommodate itself to the guard, to provide an extended cutting surface between the cutter and the teeth of the guard and to provide a self-clearing cutter construction whereby the cut material is expelled from the guard.

In accomplishing these and other objects of the invention, I have provided improved details of structure, the preferred forms of which are illustrated in the accompanying drawing, wherein:

Fig. 1 is a perspective view of a shearing device constructed in accordance with my invention.

Fig. 2 is a similar view showing the parts of the shearing device in disassembled spaced relation to better illustrate their construction.

Fig. 3 is an enlarged, longitudinal, section through the device.

Fig. 4 is an enlarged cross-sectional view 30 through guard and cutter on the line 4—4, Fig. 3.

Fig. 5 is an enlarged, perspective view of a fragmentary portion of the cutter, particularly illustrating the cutting teeth thereon.

Fig. 6 is a cross-sectional view through a modified form of guard.

Fig. 7 is a cross-sectional view through another modified form of guard.

Referring more in detail to the drawing:

1 designates an electric motor, preferably of suitable shape and dimensions to form a handle by which the shearing device may be readily manipulated, as later described. In the illustrated instance, the motor includes a cylindrical housing 2 enclosing the motor mechanism indicated by 45 the armature shaft 3 and a switch 4 for controlling current to the motor which is supplied from an ordinary light socket through the wires 5. The end of the armature shaft 3 is tubular and projects from the end of the motor housing to form 50 a drive connection for the cutter mechanism now to be described.

Mounted on the end of the motor casing opposite the switch 4 is a tubular bracket 6 having a base flange 7 provided with openings 8 through 55 which screws 9 are extended to secure the bracket

to the end of the motor housing in axial alignment with the shaft 3. The bracket 6 also includes a truncated cone-shaped neck portion 10 provided with internal threads 11 to mount a bracket extension 12.

The extension 12 includes a cone-shaped body portion 13 having a reduced threaded shank 14 forming an annular stop shoulder 15 with the body portion. The outer end of the body portion terminates in a cylindrical neck 16 having external threads 17 for mounting the guard 18, later described.

The shank 14 of the bracket extension is threadedly engaged in the threads 11 of the bracket and the shoulder 15 thereof is drawn into engagement with the end face 19 of the bracket to prevent rotation of the extension when the cutter is in operation.

The cutter guard 18 includes a hollow truncated sleeve portion 20 having an internally threaded cylindrical base 21 mounted on the threaded neck 16 of the bracket extension and which is retained against rotation thereon by a ring type lock nut 22 having internal threads 23 for receiving the threads 17 and having its end 24 arranged for frictionally engaging the end face 25 of the guard, as clearly shown in Fig. 3. The outer periphery of the lock nut is preferably knurled, as at 26, so that it may be readily grasped by the fingers and moved into tight relation with the end of the guard after adjustment thereof relatively to the cutter, as later described.

The forward portion 20 of the guard is provided with a cone shaped bore 27 in which is rotatably mounted the cutter 28 and which has a series of openings 29 to form outlets for the material cut by the shearing device.

The conical portion of the guard is provided on the side opposite the openings 29 with a series of annularly arranged slots 30 forming spaced teeth 31 extending in angular relation to the axis of the guard to form angular cutting faces 32 on the side edge thereof in the direction of the motor to cooperate with the blade of the cutter to provide a shearing cut, as later described. The side of the guard carrying the teeth is preferably reduced in thickness at the center of the teeth, as at 33, and the ends of the teeth are of increased thickness toward their base, as at 34 and 35 where they join the body or back portion 36 of the guard, as clearly illustrated in Fig. 4.

Formed on the surface of the guard at opposite sides of the thinnest portion of the teeth are spaced longitudinal ribs or combs 37 and 38 forming supports for engaging the surface over 55

which the shearing device is moved, as later described, to comb the cut material into cutting relation with the teeth and to gauge the degree of cut afforded by the cutter. In the case of a 5 razor, the combs also permit the skin to cup upwardly therebetween so that a close shave is afforded.

The cutter 28 includes a conical spiral ribbon 39 conforming in diameter and taper to the inner conical bore of the guard, so that the outer peripheries 40 of the spiral move in sliding contact with the inner face 41 of the guard teeth and across the cutting edges 32 upon rotation of the spiral. The base 42 of the spiral terminates in a series of closely wound coils 43 having internal threads 44 by which the cutter is mounted on a flexible drive member 46, as now to be described.

The drive member 46 includes a flexible shaft 20 portion 47 extending through an axial bore 48 in the bracket extension 12 and has its inner end provided with a slotted coupling member 49 received within the tubular end of the armature shaft 3. The slot in the coupling engages a pin 25 50 having its ends mounted in the opposite walls of the shaft to provide a driving connection between the armature and the flexible portion of the driving member.

The opposite end of the driving shaft carries 30 a threaded head 52 fixed securely thereon and having external threads 53 for engaging the threads 44 of the cutter and having an annular collar or shoulder portion 54 for tightly engaging the end face of the first of the coils 43 so that 35 when the cutter is threaded on the head, the flange 54 thereof will prevent rotation of the cutter independently of the rotation of the shaft.

In order to prevent longitudinal movement of 40 the cutter and its drive shaft relatively to the motor, the flexible portion of the drive shaft is provided with a sleeve 55 fixed thereto at a point within an enlarged portion 56 of the bore 48. The sleeve 55 carries an annular flange 57 of suitable diameter to be received in the enlarged 45 portion of the bore to be anchored between spaced anti-friction bearing sets 58 and 59 having their opposite sides respectively engaging the end 60 of an enlarged portion of the bore and a washer 61 slidable on the sleeve at the end adjacent the motor.

The washer 61 is retained snugly against the bearing set 54 and the bearing set 58 against the shoulder 60 by a coil spring 62 coiled about the flexible portion of the shaft and having one 55 end bearing against the washer 61 and its opposite end against the sleeve 63 threaded in the end of the bore for adjusting tension of the spring.

It is thus apparent that when the bearing sets 60 58 and 59 are in position and retained by the spring and threaded sleeve 63, the driving member is prevented from movement in either direction relatively to the bracket extension. The spiral cutter will, therefore, be retained in fixed 65 relation relatively to the guard 20 to maintain the desired contact between the cutter and the inner surface of the guard.

In order to enhance the cutting properties of 70 the spiral cutter, the innerface thereof is preferably provided with a series of V-shaped teeth or ribs 64 which cooperate with the periphery of the spiral to form a series of serrated teeth 65 along the cutting edge thereof. The trailing portion of the spiral ribbon is preferably reduced in diameter from substantially the center thereof, as

indicated at 66, so that only a narrow portion 67 is in contact with the guard. This is an important feature for the reason that as the ribbon wears relatively to the guard, the teeth 65 will retain their shape due to the fact that wear has 5 no effect other than shortening the length of the ribs 64.

In order to prevent cut material from being emitted through the end of the guard the opening therein is closed by a suitable cap 69 having 10 a rounded portion to prevent injury to the surface being sheared by the sharp terminal edge of the guard.

In Fig. 6 is illustrated a modified form of the invention, wherein the toothed edge 68 of the 15 spiral cooperates with a cutting edge 70 on the guard 71 so that the material cut by the guard is not only cut along the sides of the teeth, as in the preferred form, but against the ends of the cutting edge 70 as well.

The form of cutter illustrated in Fig. 7 is substantially the same as that illustrated in Fig. 6, except that the teeth extend at right angles to the axis of the cutter and the guard is provided with a slot 72 for accommodating the hair or 25 material to be cut.

Since the guards shown in Figs. 6 and 7 operate against cutting edges 70, it is necessary to provide only one rib or comb 37 for gauging the amount of cut of the shearing device.

In using the preferred form of the device constructed and assembled as described, the guard is moved angularly back and forth across the surface being sheared in the direction of the teeth, so that the ribs act as a comb and the hair 35 enters between the teeth to be sheared off by the spiral cutter as the flights thereof move across the cutting edges of the teeth.

When cut, the hairs are expelled through the openings 29 by the propelling action of the 40 spirals.

To tighten the shearing tension of the cutter relatively to the guard, the ring 22 is loosened by slackening it from the end of the guard.

The guard is then moved retractively toward 45 the direction of the motor to cause the cutter to enter farther into the conical bore of the guard. The spiral form of the cutter provides sufficient inherent tension to retain the teeth thereof in proper cutting relation with the teeth of the 50 guard. When the proper adjustment is made, the ring 22 is retightened against the guard to prevent rotation thereof on the bracket extension.

Owing to the ribs or combs 37 and 38, a very close cut is afforded because pressure of the 55 guard against the surface being sheared presses the surface upwardly therebetween in close contact with the cutting edge of the cutter.

The forms of the invention illustrated in Figs. 6 and 7 are used in like manner except that they 60 are moved in a single direction across the surface being sheared since they cut only against the cutting edges 70.

What I claim and desire to secure by Letters Patent is:

1. In a device of the character described, a 65 guard support, a toothed guard on the support, a cutter including a flexible helical ribbon rotatable within the guard and having teeth cooperating with the teeth of the guard, and means rotatably mounted in the guard support for rotating the cutter.

2. In a device of the character described, a support, a tapered tubular guard adjustably mounted on the support having angularly arranged 75

- teeth, a helical ribbon-like cutter having a series of closely wound coils terminating in flights rotatable within the guard about the axis of said flights and in shearing contact with said teeth, a shaft having a head mounting said closely wound coils of the cutter, antifriction means mounting the shaft in the guard, and means for rotating the shaft.
3. In a device of the character described, a guard support, a guard adjustably mounted on the support and having a series of spaced slots forming teeth, a helical ribbon-like cutter having a series of closely wound coils terminating in flights rotatable within the guard about the axis of said flights and in shearing contact with said teeth, a head mounting said closely wound coils of the cutter, means mounting the head in the guard support, and means for rotating the head.
4. In a device of the character described, a guard support, a guard mounted on the support and having a series of spaced slots to form teeth, a helical ribbon-like cutter having a series of closely wound coils terminating in flights rotatable within the guard about the axis of said flights and in shearing contact with said teeth, a head mounting said closely wound coils of the cutter, means mounting the head in the guard support, and means for rotating the head.
5. In a device of the character described, a support, a guard fixed on the support, a cutter rotatably mounted in the guard including a single flexible ribbon coiled to form a helical cutting edge having free movement laterally from the longitudinal axis of said cutter whereby the helical cutting edge is maintained in cooperative cutting contact with the guard, and means connected with the support for rotating the cutter.
6. In a device of the character described, a support, a tapered tubular guard fixed to the support and having teeth, a cutter rotatably mounted in the guard including a single flexible ribbon coiled to form a helical cutting edge having free movement laterally from the longitudinal axis of said cutter whereby the helical cutting edge is maintained in cooperative cutting contact with the teeth of the guard, and means connected with the support for rotating the cutter.
7. In a device of the character described, a support, a toothed tubular guard fixed on the support, a cutter rotatably mounted on the guard including a single flexible ribbon coiled to form a helical cutting edge having free movement laterally from the longitudinal axis of said cutter whereby the helical cutting edge is maintained in cooperative cutting contact with the teeth of the guard, and means connected with the support for rotating the cutter.
8. In a device of the character described, a support, a tubular guard member fixed on the support, a cutter member rotatably mounted in the guard including a single flexible ribbon coiled to form a helical cutting edge having cooperative cutting contact with the guard, means for adjusting one of said members relatively to the other to vary pressure of said contact, and means connected with the support for rotating the cutter member.
9. In a device of the character described, a support, a tapered tubular guard adjustably mounted on the support having angularly arranged teeth and ribs extending longitudinally of the guard and transversely of the teeth, a helically coiled ribbon-like cutter having flights rotatable within the guard about the axis of said flights and in shearing contact with said teeth, and flexible means mounting the cutter for free bearing support by the guard.
10. In a device of the character described, a support, a tapered tubular guard adjustably mounted on the support and having angularly arranged teeth and ribs extending longitudinally of the guard and transversely of the teeth, a helical ribbon forming a flexible cutter having flights rotatable within the guard about the axis of said flights and retained in shearing contact with said teeth incidental to flexibility of the cutter, and flexible means mounting the cutter for bearing support in the guard.
11. In a device of the character described, a support, a tubular guard fixed on the support and having a series of spaced slots forming teeth, a cutter mounted in the guard including a single flexible ribbon coiled to form a helical cutting edge having free movement laterally from the longitudinal axis of said cutter whereby the helical cutting edge is maintained in cooperative cutting contact with the teeth of the guard, and means connected with the support for moving the cutter over said teeth.

ARTIE B. HARRIS.
